RAYMOND JOSEPH MOLINIÉ, OF LYON, FRANCE.

BARROW FOR CARRYING STRETCHERS FOR WOUNDED.

1,242,887.

Specification of Letters Patent.

Patented Oct. 9, 1917.

Application filed July 7, 1917. Serial No. 179,236.

To all whom it may concern:

Be it known that I, RAYMOND JOSEPH MOLINIÉ, a citizen of the Republic of France, and resident of Lyon, France, (Hôpital No. 5 44, Place Morel), have invented a new and useful Barrow for Carrying Stretchers for Wounded, which barrow is fully set forth in the following specification.

This invention relates to a barrow for 10 carrying stretchers for wounded, of reduced dimensions so that it can take shelter behind the smallest obstacles, and can be wheeled over any ground, pass over any obstacles and travel on any paths and roads accessible to 15 stretcher bearers. This apparatus can be moreover easily taken to pieces; its weight and the space occupied are so small that it can be easily carried by one man.

In order to make the following explanation as clear as possible, a construction of 20 the stretcher carrying barrow according to this invention is illustrated, by way of example, in the accompanying drawing.

Figure 1 shows in perspective the 25 stretcher carrying barrow fitted up, the axle connecting together the two wheels being however removed for the sake of clearness.

Fig. 2 shows the barrow folded, the various parts constituting the same being tied to 30 each other for the purpose of facilitating transport.

Fig. 3 is a side elevation of the barrow with a stretcher placed on it.

Fig. 4 shows in section—on an enlarged 35 scale—one of the cramps by means of which the stretcher can be secured to the barrow.

Fig. 5 is a section of one of the ends of the axle; the other end being symmetrical to the first, it has not been shown.

40 The apparatus could be made of any suitable material, for instance of metal, and in such case it is preferable to use for its construction technical iron sections; U-irons, double T-irons, etc., but it could also be 45 made of wood, and it is of this material that the barrow is made, shown by way of example, in the accompanying drawing. In this case are used, timbers placed edgewise, whether armored or not, of a cross section 50 similar to that of the timbers used for instance for making the legs of photographic apparatus.

The apparatus chiefly comprises two uprights or supports *a* identical with each 55 other, two wheels *b* identical with each other,

and finally the axle *c* connecting together the two wheels.

Each of the parts constituting the apparatus, will be successively described.

One support *a* is made of a rectilinear 60 wooden part made from two wooden plates *a'* *a''* placed edgewise and connected together at intervals by blocks *d*, also of wood, secured by means of screws *e*. At one of its ends, the support *a* is connected to a blade, 65 or to several superposed blades *f* forming a spring; the connection is insured by means of screws *g* penetrating into an armature *d* connecting together the two plates *a'* *a''*. To the other end is pivoted a leg *h*, also 70 made of armored wood, like the support *a* proper. The hinging is effected about a pin *i* terminating in a thumb nut which enables the leg to be locked relatively to the support *a*, whatever be the position which it is occupying. The spring *f* which is semi-circular 75 in shape, terminates in a bearing *j* of square cross-section, with which engages, as shown by the figure on an enlarged scale, the square end *j'* of the axle.

It goes without saying that the supports *a* and the legs *h*, instead of being constituted by wooden plates connected together by blocks *d*, could be constituted by single pieces of wood perforated or recessed after the operation, the blocks *d* forming then one piece with the blades *a'* *a''*. When the barrow is fitted up, the two supports *a* are secured 80 together not only by the stretcher when it is placed on the barrow, but also, on the one hand, by the axle connecting together the two wheels, and on the other hand, by rods or braces *k* connecting together the two legs.

When the apparatus is fitted up as shown in Fig. 1 (the axle having been of course put 85 in place), the stretcher is placed on the supports *a* as shown in Fig. 3; the longitudinal members *l* of the stretcher being the same distance apart as the supports *a*, each longitudinal member will be, as shown in Fig. 100 4, exactly over the corresponding supports *a*. In order to secure the stretcher to the support in a reliable manner, there could be obviously used any suitable means, for instance cramps *m* movable along sleeves *n* secured to the supports, a nut *o* with several lock nuts if necessary securing the position of the cramp as shown in Fig. 4. When the stretcher is to be taken off from the barrow, the nut *o* and the locknut are unscrewed,

and the cramp *m* is turned so that its horizontal branch *m'* releases the longitudinal member *l* of the stretcher. Two cramps arranged on each support, are sufficient to secure the stretcher to the barrow in a reliable manner. When the stretcher is thus fixed on the barrow, the whole apparatus is moved on the ground by pulling or by pushing, or by both simultaneously, the ends or handles 10 of the stretcher.

When the barrow is to be taken to pieces, the axle is removed first, which can be easily done by bringing the cramps *p* into their horizontal position; one of the supports *a*, 15 and then the other are withdrawn; this having been done, the axle is removed from the two wheels *b*; the supports *a* are then placed side by side as shown in Fig. 2, the legs are folded against the supports, and the axle 20 having been placed below, the whole is tied together by suitable means. The wheels are then mounted on cramps or short pins *q* pivoted to the outer surfaces of the supports *a*. When the barrow is assembled, the 25 cramps *q* are folded against the supports *a* (Fig. 3), while they are placed normally to the supports when the barrow is taken to pieces (Fig. 2). When the apparatus is fitted as shown in Fig. 3, it is possible, not 30 only, as already stated, easily and quickly to carry a stretcher on various ground; but it forms moreover a real table which enables the surgeon to bandage the wounded without having to kneel or to bend on the ground; the bandaging is facilitated, made more 35 rapid, and the bandaging articles do not come into contact with the ground, which insures better aseptic treatment.

Copies of this patent may be obtained for five cents each, by addressing the "Commissioner of Patents, Washington, D. C."

Claims:

1. A barrow for carrying stretchers for wounded, chiefly characterized by two supports, two legs pivoted to the supports, two spring blades secured to the said supports, two detachable wheels mounted on an also detachable axle connecting together the ends 45 of the two springs, means of attachment for securing a stretcher to the supports when the barrow is fitted up.

2. A barrow for carrying stretchers for wounded, chiefly characterized by two supports made of two wooden plates with connecting blocks, two legs pivoted to the said supports with hinged connection rods or ties, two semi-circular springs with superposed blades, secured to the supports and 50 terminating in bearings intended to receive a detachable axle; detachable wheels capable of being mounted on the axle, means of attachments for securing a stretcher to the supports when the barrow is fitted up. 55

3. A barrow for carrying stretchers for wounded, chiefly characterized by two supports which, when the barrow is taken to pieces, can be placed side by side, two legs folded to the supports, an axle placed parallel to and along the supports, means tying 60 the whole together, pivoted cramps on the supports intended to receive the wheels.

In testimony whereof I have signed this specification in the presence of two subscribing witnesses. 70

RAYMOND JOSEPH MOLINIÉ.
